Filed Apr. 20, 1962, Ser. No. 69,787

Term of patent 14 years

(Cl. D72—1)

FIG. 1.

FIG. 2.

FIG. 3.

FIG. 4.

FIGURE 1 is a perspective view from above of a flare holder showing my new design;

FIGURE 2 is a side elevational view of the flare holder as seen from the opposite side of FIGURE 1, as shown in conjunction with a pot type flare and a fragmentary portion of a horizontal support member, both of the latter being shown in broken lines for illustrative purposes only;

FIG. 3 is an end elevational view of the flare holder as shown in FIG. 2; and

FIGURE 4 is a fragmentary bottom plan view of the flare holder of FIGURES 1, 2 and 3.

I claim:

The ornamental design for a flare holder or similar article, substantially as shown and described.
